UNITED STATES PATENT OFFICE.

JOHN EGER, OF GEARY, OKLAHOMA.

SOCKET.

1,330,248.

Specification of Letters Patent. Patented Feb. 10, 1920.

Application filed November 1, 1918. Serial No. 260,738.

To all whom it may concern:

Be it known that I, JOHN EGER, a citizen of the United States, residing at Geary, in the county of Blaine and State of Oklahoma, 5 have invented certain new and useful Improvements in Sockets, of which the following is a specification.

This invention relates to drill extractors adapted to provide for conveniently removing 10 drill stems from well pipes or holes.

The primary object of the invention is to provide a device of this character which includes a stem receiving socket having guide means associated therewith for the 15 purpose of engaging the stem and properly guiding the same into the socket for engagement with the gripping means carried thereby.

Another object of the invention resides in 20 the provision of means for automatically throwing the guide members into operative position to act as finders for locating and guiding the stem into the socket.

Another object of the invention resides in 25 the details of construction, combination and arrangement of parts, whereby the device is rendered practical efficient and comparatively cheap of manufacture.

In the drawings:

30 Figure 1 is a view in elevation of the improved socket.

Fig. 2 is a longitudinal sectional view taken through the socket in a plane at right angles to that of Fig. 1.

35 Fig. 3 is a view of a modified form showing the socket in elevation and the guide members in section to illustrate the manner of attaching the latter.

Fig. 4 is a view taken on the line 4—4 40 of Fig. 2.

Referring to the drawings, 1 indicates the socket which is provided with the usual vertical stem receiving bore 2 opening into the lower end of the socket. Adjacent the 45 upper end of this bore, the socket is provided with oppositely arranged side slots indicated at 3 in which are mounted suitable gripping members 4 adapted to engage and clamp the stem as the latter enters the bore 50 2. These gripping members 4 form no part of the present invention and hence may be of any suitable standard type used in connection with sockets of this character. In the present instance, however, the gripping 55 members are shown as in the form of pivoted clamping members having springs 5 asso-

ciated with the pivots thereof to force the members into proper engagement with the stem as will be later set forth.

At the lower end thereof the stem is reduced as indicated at 6 and 7 thus providing the superimposed annular shoulders 8 and 9. Beneath the shoulder 9 and upon opposite sides of the socket are formed two pairs of ears indicated respectively by the numerals 10 and 11. Pivoted between the ears 10 by means of the pivot bolt 12 is an ear 13 carried by the upper end of the swinging guard member 14. This guard member 14 is semi-circular to embrace the reduced portion 6 and 7 of the sprocket and co-operates with a duplicate guard member 15. This latter guard member is attached to the socket in exactly the same manner being provided at its upper end with an ear 16 which is pivotally secured between the ears 11 by means of a pivot bolt 17. Each of these guard members is provided upon its inner face with a semi-circular enlargement 18 having the upper edge thereof fitting beneath the annular shoulder 8 and the lower edge thereof beveled as indicated at 19. At the lower edges thereof the inner faces of these guard members 14 and 15 are also beveled as indicated at 20 so as to engage 85 and gradually guide the stems within the space between the guard members.

Extending through and connecting the guide members 14 and 15 upon opposite sides of the reduced lower end 6 of the socket are 90 a pair of guide bolts 21. These bolts extend through the members 14 and 15 as shown in Fig. 4 and are equipped at one end with heads 22. The opposite ends thereof have nuts 23 threadedly engaged thereon. The 95 inner opposing faces of these guide members 14 and 15 are recessed to provide opposing seats 24 and 25 which surround the guide bolts as shown and are adapted to support the springs 26 which embrace the guide 100 bolts and act upon the seats 24 and 25 to spread the guide members apart so that the same will engage the wall of the opening in which the socket is inserted and will thus come into contact with the stem to drive 105 the latter into the bore 2 for engagement with the gripping members 4.

In the modification shown in Fig. 3, the shape of the guide members indicated at 27 and 28 is slightly different from that previously set forth but the guide members are attached to the socket in exactly the same

manner. In this form, the guide members 27 and 28 are made flaring at their lower end, substantially as shown. Each of these guide members is made of gradually increasing thickness toward the upper end thereof and at a point spaced from said upper end is reduced to provide an annular shoulder 29 which is engageable with the annular shoulder 8 of the socket. The portion of each member 27 and 28 above the shoulder 29 is adapted to closely embrace the reduced portion of the socket indicated at 7 as seen in Fig. 2 and is secured to the socket in the same manner as the guide members 14 and 15 previously described. The portion of the members below the shoulders 29 is adapted to embrace the reduced portion 6 as seen in Fig. 2 of the socket and to extend beyond said reduced portion in the flaring manner indicated. In this form the guide bolts 21 and 22 and the springs coöperating therewith will be also used as intimated, but further description of these parts is deemed to be unnecessary.

In the use of the device when using the form of socket shown in Fig. 2 it will be evident that the guide members 14 and 15 will automatically separate when entering the hole due to the action of the springs provided for this purpose. Thus the beveled edges 20 of these members will scrape the wall of the opening or pipe in which the socket is inserted and will thus insure contact with the stem to be extracted. These beveled edges will guide the stems into the space between the guide members and subsequent contact of the stem with the beveled edges 19 of the enlargement 18 will cause the stem to be guided into the bore 2 in which it will be grasped by the gripping members 4. In using the smaller socket shown in Fig. 3 the action is substantially the same with the exception that the curved or tapering inner wall of the members 27 and 28 will guide the stem directly into the bore 2 thus doing away with the necessity of providing the inclined edges 19 and 20 for this purpose. The form shown in Fig. 2 is what might be termed a straight socket particularly adapted for use within well holes of relatively small circumference,

while the form shown in Fig. 3 is adapted for holes of wider circumference in which the spread of the members 14 and 15 of the first mentioned form might not be sufficient 55 to insure proper engagement with the drill stem.

The foregoing description and accompanying drawings have reference to what might be considered to be the preferred or 60 approved form of my invention. I desire it to be understood that I may make such changes in the construction, combination and arrangement of parts, materials, dimensions, etc., as may prove expedient and 65 fall within the scope of the appended claims.

Having thus fully described my invention what I claim as new and desire to secure by Letters Patent, is:—

1. A drill stem extracting device comprising a socket, guide members conforming to the contour of the socket, and having their upper ends hingedly connected thereto, their lower ends being extended beyond the 75 lower end of the socket, the said lower end being provided with guide bolts extending through and connecting said members, each of the said guide bolts having a spring surrounding the shank of the bolt and engaging the opposing faces of the said guide members to exert a pressure thereon for forcing the said guide members away from each other.

2. A drill stem extracting device comprising a socket, guide members conforming to the contour of the socket, and hingedly connected thereto, the lower ends of the guide members being extended beyond the lower end of the socket, tangentially disposed bolts 90 arranged in diametrically opposite sides of the guide members and extending through openings formed therein, and a coil spring surrounding each guide bolt and having its ends in engagement with the said guide members to cause the separation thereof.

In testimony whereof I affix my signature in presence of two witnesses.

JOHN EGER.
